UNITED STATES PATENT OFFICE.

CHARLES F. NORRIS, OF NEW YORK, N. Y.

CAR-VENTILATOR.

SPECIFICATION forming part of Letters Patent No. 239,188, dated March 22, 1881.

Application filed January 26, 1881. (No model.)

To all whom it may concern:

Be it known that I, CHARLES F. NORRIS, of New York, in the county of New York, and in the State of New York, have invented certain new and useful Improvements in Car-Ventilators; and I do hereby declare that the following is a full, clear, and exact description of the invention, reference being had to the accompanying drawings, and to the letters of reference marked thereon, making a part of this specification.

This invention relates to certain improvements in car-ventilators; and it has for its objects to provide a means whereby the foul air may be permitted to escape at the top of the car without the admission of drafts of cold air or smoke or cinders from the engine, as more fully hereinafter specified. These objects I attain by the mechanism illustrated in the accompanying drawings, in which—

Figure 1 represents a perspective view of my invention, and Fig. 2 a sectional view thereof.

The letter A indicates the top of the car, and B an opening therein.

C indicates a transverse ridge, mounted on opposite ends upon the angular supports D. The said ridge, on its under side, is rabbeted, as indicated by the letter E, the rabbets forming seats for the edges of the hinged lids F, 30 which are pivoted in the rabbets by means of

the bolts G. The said lids, when in a normal position, set against the inclined sides of the angular supports D, and close the openings at the opposite sides of the same. The lids may be provided with any suitable means by which 35 they can be elevated and held in an elevated position.

When in use on a car the lid toward the rear of the car is elevated, the other one being kept down. It is evident that the smoke or cinders from the engine cannot pass into the car while the lids are in this position, and that nevertheless a free escape for the foul air from within the car is provided.

Having thus described my invention, what I 45 claim, and desire to secure by Letters Patent, is—

In combination with the roof of a car, having an opening therein, the rabbeted transverse ridge, mounted on angular supports, and 50 the hinged lids adapted to be opened or closed, substantially as specified.

In testimony that I claim the foregoing I have hereunto set my hand and seal this 20th day of January, 1881.

CHARLES F. NORRIS. [L. S.]
